This invention relates to a calculating machine for extracting square root. More particularly the invention relates to a means for extending the number of orders in the machine from which the root of a radicand can be extracted without redesigning or changing the timing of the commercial square root calculating machine. Thus, the present invention is an improvement of United States Patent No. 2,736,494, issued February 28, 1956, to myself and another.

The machine in which the present invention is constructed is the same as that described in the above patent, No. 2,736,494, except that the present machine is a twelve-order machine rather than a ten-order machine and includes two more ordinal rows of value, or selection, keys, two additional accumulator dials, two more counter dials, and two additional square root initiating keys than shown in that patent.

Soon after the introduction of my square root calculating machine on the market, there was recognized a need, in some cases, for a twelve-order machine from which the root of a radicand could be extracted. It was found that to construct such a mechanism in a machine following the teachings of my patent, No. 2,736,494, would require a complete change in the overall design of that machine, since the machine timing, tens-transfer mechanism, digitation mechanism, as well as the mechanism for shifting the carriage, would be involved. The cost of such a redesign of the ten-order square root machine could not be justified by the demand that could be expected for a twelve-order machine to warrant the expenditure of such a large sum of money. It was not until my present invention that there was found a way around this exasperating problem wherein a twelve-order machine can be built without completely redesigning the commercial square root calculator, simply by adding more square root control cams telescopically on the cam shaft and mechanism for controlling the cams in timed relationship with the rotation of the cam shaft. Thus, a primary object of the invention is to provide a calculating machine for extracting a square root in which the orders from which the root can be extracted are extended.

Another object of the present invention is to provide a

square root calculating machine wherein the number of orders from which the root can be extracted are extended without changing the timing of the basic machine.

Still another object of the invention is to provide an adjustable square root cam shaft, which cam shaft is rotated through more than 360° without the cams associated with the lower order interfering with the operation of those cams associated with the higher orders, and vice versa, while maintaining the same timing as in prior machines.

Further objects and advantages will become apparent from the following description of a preferred embodiment of the present invention, taken together with the accompanying drawings in which:

FIG. 1 is a fragmentary plan view of the square root cam shaft showing the mechanism for controlling the axial positions of the cams;

FIG. 2 is a front view of the square root programming mechanism, the view being taken along the vertical planes indicated by the lines 2—2 of FIG. 1;

FIG. 3 is an enlarged front view of the drive mechanism operative to condition the square root programming mechanism, the view being taken along the vertical plane indicated by the line 3—3 of FIG. 1;

FIG. 4 is an enlarged plan view of the mechanism for latching the extended square root mechanism in operative position, the view taken along a plane parallel to the top of the machine, as indicated by line 4—4 of FIG. 3;

FIG. 5 is a fragmentary view of the square root cam shaft positioning mechanism, taken from the right side, such as taken along the vertical planes indicated by the lines 5—5 of FIG. 3;

FIG. 6 is a detailed drawing showing the means for rocking the twelfth order gear-engaging arm to permit initiation of the square root extraction operation, the view being taken along the vertical plane indicated by the line 6—6 of FIG. 3;

FIG. 7 is a longitudinal cross-sectional view through the square root programming mechanism taken along the plane indicated by line 7—7 of FIG. 2;

FIG. 8 is a detailed cross-sectional drawing of the eleventh and twelfth square root cams, the view being taken along the vertical plane indicated by the line 8—8 of FIG. 1; and

FIG. 9 is a fragmentary cross-sectional view showing the cam shaft aligner mechanism, the view being taken along the planes indicated by the lines 9—9 of FIG. 1.

The extraction of square root can be considered as the performance of a division operation with a progressively changing divisor, i.e., one in which the divisor is changed automatically between each cycle of operation. This is accomplished in the above-mentioned commercial Square Root Machine by utilizing the conventional division mechanism, of the type disclosed in the patent, No. 2,229,889, issued to Carl M. F. Friden on January 27, 1941, to maintain the machine in continuous operation, and continuing the subtraction to an overdraft. The overdraft mechanism enables the division programming mechanism to cause a multicyclic operation, the first of which adds back the value which caused the overdraft, the second cycle then shifts the carriage one order to the left, and finally, the third cycle initiates another continuous subtractive operation.

The above-noted division programming operation is used in the present machine to the extent, as mentioned in my above patent, that interordinal changes are controlled by sensing an overdraft and then initiating operation of the division programming mechanism. The extraction of square root, however, differs from conventional division in that the divisor is changed in each cycle according to the progression described in my patent, No. 2,736,494. In the "5's" method of that patent this progression re-

sults in the subtraction of the value of "5" in the predetermined order in the first cycle of operation, and in each successive cycle the value is increased by "10" (or "1" in the next higher order) until the operation causes an overdraft. Thereupon, the overdraft is automatically corrected and the carriage is shifted one order to the left. Substantially simultaneously with the shifting of the carriage, the "5" is erased and inserted in the next lower order, the value standing in the tens order of the previous series of the divisor remaining unchanged. In the first cycle of operation after the carriage is shifted, the value standing in the tens order of the divisor at the time of the overdraft constitutes the value standing in the hundreds order, the first cycle subtracting that value plus "05". Each successive cycle progressively changes this value by increasing it by "10", so that the second cycle will have "15" standing in the lower orders of the divisor, the hundreds value remaining unchanged. This second series of operations is continued to an overdraft, after which the overdraft is corrected and the carriage again shifts to the left, and the operation repeated.

I. GENERAL DESCRIPTION

Without reference to the drawings it will be understood that the machine in which the present invention is embodied is provided with the usual mechanisms, such as the selection mechanism, the accumulator, a tens-transfer mechanism, means for effecting the shifting of the accumulator in either direction, and means for automatically dividing a dividend by a divisor. Because the above-mentioned components are old per se, it is believed unnecessary to describe them herein, and for a full and complete description thereof, reference may be made to either of the above-mentioned patents.

II. SQUARE ROOT MECHANISM

(a) General

At the beginning of this disclosure it was mentioned that the present machine is similar to that disclosed in my patent, No. 2,736,494, so the basic mechanism will not be described herein. It will be assumed that operation will be initiated by depression of an initiating key, that operation of such a key will automatically shift the accumulator carriage to the proper ordinal position, and the radicand inserted five times in the accumulator.

It can be noted, however, that in my present machine the carriage is automatically shifted in the highest ordinal position (the twelfth, in this case, as contrasted to the tenth in my prior patent) when there is an even number of whole digits in the radicand, or in the adjacent ordinal position when there is an odd number of whole digits in the radicand; and that after the entry of the radicand, an additional shift is attempted which is ineffective if the carriage is already in that position, i.e., if there is an even number of whole digits in the radicand.

(b) Square Root Programming Mechanism (FIGS. 1, 3 to 6)

As mentioned in my earlier patent, means is provided for blocking operation of the square root programming mechanism until the register carriage is in its extreme right-hand position, in those cases where a shift occurs after entry of the radicand factor. This blocking means is under control of a delay latch shown particularly in FIG. 25 of Patent No. 2,736,494 and is effective to control operation of the square root control shaft 20 (see FIGS. 1, 5 and 6). As explained in the above-mentioned patent, the control shaft 20 is first rocked clockwise, as viewed in FIGS. 5 and 6, and thereafter latched in that position by the delay latch for the machine cycles required for entering the radicand five times into the accumulator. During the next-to-the-last of the entry cycles the division mechanism is set for operation by the above-mentioned means, but actual initiation of division is prevented until the start of the next cycle. The delay latch

is released at approximately the 90° point in this final entry cycle which, in turn, releases the shaft 20 and the mechanism controlled thereby, as will be described hereinafter. During the last cycle of this programmed entry operation, the conventional division aligner mechanism is conditioned to shift the register carriage to its extreme right-hand position, if not already there. If the carriage is already in its extreme position, the aligner mechanism starts the first of three idle aligning cycles to release and enable the usual carriage shift mechanism. Thus, in the last entry cycle, the shaft 20 is rocked sharply counterclockwise by means of a strong spring (not shown) to its normal, or home position. The rocking of the shaft 20, as it is restored to its normal position, operates a mechanism for controlling the square root programming mechanism. This control mechanism comprises two arms: The first arm 21 (FIG. 5) causes a shifting of the square root cam shaft (of the selection programming mechanism) into operative position if the carriage is in its extreme right-hand position, and conditions a mechanism for such shifting as soon as the carriage is in its extreme position, if the entry of the radicand factor occurred in the next to the last carriage position; and the second arm 41 (FIG. 6) operates a mechanism which inserts a value of "5" in the eleventh order of the keyboard, thereby providing the first subtraction of "5" in the first digitation cycle as is required to carry out the program of square root extraction.

(1) *Cam shaft shift.*—The first mentioned of these mechanisms comprises the arm 21 (see particularly FIG. 5) depending from, and rigidly fixed to, the control shaft 20. Rockably mounted on the lower end of the arm 21 is a pusher arm 22, which is urged upwardly by a suitable spring 23 tensioned between the two arms. The pusher arm 22 extends rearwardly (to the right in FIG. 5) and at its rearward end is provided with a suitable latching shoulder 24 adapted to engage and operate a cam shaft shift lever 25 (see also FIGS. 1 and 4). This lever 25 is rocked, as will be explained hereinafter, if the program mechanism has been operated through five machine cycles, and a division operation has been initiated. The pusher arm 22 is also provided with a stud 26 for rendering the arm 22 inoperative in all operations except division. The desired control for rendering arm 22 inoperative in all operations of the machine except division is preferably secured by means of a long link 27. This link 27 is the same as link 915 shown in FIG. 40 of my patent, No. 2,736,494, and is urged upwardly by means controlled by the division mechanism, as described in that patent. An ear 28 at the upper end of link 27 overlies and engages the stud 26. The division shaft, as pointed out in the above-mentioned patent, is rocked at the very outset of a division operation and causes upward movement of link 27. If shaft 20 has been rocked (clockwise in FIG. 5), upward movement of link 27 permits the pusher arm 22 to rise and engage the lever 25. It can be seen that unless the control shaft 20 is rocked clockwise, the upward movement of link 27 is ineffective to cause the pusher arm 22 to engage the lever 25 and shift the square root cam shaft into operative position. The pusher 22 is effective to rock the cam shaft shifting lever 25 only if the machine is conditioned for square root extraction by rocking of shaft 20 and a division operation has been initiated to lift link 27, as explained in the above-mentioned patent. However, the arm 22 is effective to rock the cam shaft shifting lever 25 when the above two preceding conditions are present.

The cam shifting lever 25 (best shown in FIG. 4) is journaled on a rivet 33 mounted in a bracket 31 extending laterally from a frame plate 32. Associated with the lever 25 is a cam shaft shifting arm 34, likewise journaled on the rivet 33. This second arm 34 is resiliently biased to follow the rocking of the lever 25 by a suitable spring 35 tensioned between an ear on lever 25 and an ear on the arm 34. The arm 34 also carries a pin 36 which

bears against the left side of a collar 37 (FIGS. 1 and 6) fixed on a square root cam shaft 38. If the square root cam shaft 38 is in proper angular position for extraction of square root (which is dependent upon the carriage being in the extreme right-hand position as will be explained hereinafter), rocking of lever 25 (clockwise in FIG. 4) will rock arm 34 to shift the cam shaft 38 to the right, or to its operative position for the extraction of square root. However, if the carriage is not in the proper position, i.e., in its next to extreme position, the lever 25 will rock and will be held in its rocked position by the shoulder 24. However, the square root cam shaft 38 is blocked against rightward shifting, by means explained in the next section, until the carriage is in its extreme position. Thus arm 22 is locked in its effective position, and spring 35 yields, until the carriage is shifted to its extreme position. Thereupon, the second arm 34, under the urgency of the spring 35, will be effective to translate the cam shaft 38 to the right to control the extraction of square root.

Upon return of the division control mechanism to its normal condition, as mentioned in my prior patent, the link 27 and hence arm 22) is pulled downwardly, whereupon the lever 25 is released from the shoulder 24 and will return to its normal position under force of the spring 35 and a spring 39 (FIG. 2) which normally urges the square root cam shaft 38 to the left.

(2) "5's" entry, adjacent highest order of keyboard (FIGS. 2, 3 and 6).—The counter-clockwise rocking of the shaft 20, in the first cycle after initiation of division, is also effective to set a value of "5" in the next to the highest order of the selection mechanism. In the conventional ten-order machine, the "5's" entry was made in the ninth order of the keyboard but, in the machine of the present invention the "5's" entry for the first ordinal operation is made in the eleventh order of the keyboard. The arm 41 is pinned on, or otherwise rigidly affixed to, the shaft 20. A pusher link 42 is journaled to the lower end of the arm 41 and, as best shown in FIG. 6, extends rearwardly adjacent the cam shaft 38 and a gear-engaging shaft 46. A suitable spring 40 is tensioned between the two arms 41 and 42 and urges the link 42 upwardly, or counter-clockwise in FIG. 6. The rearward end of the pusher link 42 is provided with two fingers. The upper finger is provided with a cam edge 43 adapted to be engaged by the conical face of the collar 37 on the square root cam shaft 38 so that the arm 42 will be rocked downwardly to disable the arm by the rightward movement of cam shaft 38. The other finger of the link 42 is notched to engage a pin 44 carried by an arm 45 rigidly mounted on the gear-engaging shaft 46. Normally the lower end of the link 41 will lie below the pin 44, as seen in FIG. 6. However, when the shaft 20 is rocked clockwise during the five additive cycles previously mentioned, the link 42 will be pulled to the left, and the spring 40 will lift it until the notch in the end thereof engages the pin 44. At the end of the five additive cycles, the keyboard will be cleared of the radicand. In the next, or sixth, cycle, the division mechanism will be tripped to initiate operation of the division control mechanism, as explained in my earlier patent; and in the seventh cycle, the shaft 20 will be released for counter-clockwise movement, whereupon the link 42 rocks arm 45 and shaft 46 clockwise in FIG. 6. If the carriage is in the extreme right-hand position, the cam shaft 38 will be shifted to the right, immediately following the translation of the link 42 and rocking of shaft 46. Translation of the cam shaft 38 to the right cause the conical face on the collar 37 to engage the cam face 43 of link 42 and cam it downwardly (clockwise in FIG. 6) to disengage the notch from the pin 44, thereby releasing the control shaft 46 from the link. If, on the other hand, the carriage is in the next to the extreme position, the cam shaft 38 and the collar 37 cannot be translated to the right until the carriage has reached the extreme right-hand

position, whereupon the link 42 will be cammed downwardly.

It should be mentioned at this point that the square root cam shaft 38 cannot be shifted to the right until the carriage is in its extreme right-hand position and the gear-engaging arm of the highest order positioning mechanism (to be mentioned hereinafter in the section entitled "Cam shaft and drive") is rocked to operative position by link 42, arm 45 and shaft 46. In every carriage position, one of the cams 50 will engage the side of the associated gear-engaging arm 70, thereby preventing shifting of the shaft 46 until the arm of that order is rocked out of the way. In the highest order, and in that order only, is means provided (i.e., link 42) for rocking the gear-engaging arm out of the way. Also, it can be noted that the rocking of the shaft 46 is operative to rock the highest order gear-engaging arm to insert the value of "5" in the next lower order of the selection mechanism. The highest order gear-engaging arm is held in its operative position by the corresponding cam on the square root cam shaft 38, and is so held until the carriage shifts from the extreme position at the termination of the first ordinal series of operations in the extraction of square root.

(c) Square Root Selection Mechanism

The cam shaft 38 (as in my prior patent) is normally biased to the left, as shown in FIG. 2, by the spring 39 encircling the shaft and seated between the end plate 49 of the square root control box and the previously mentioned collar 37. However, when the cam shaft shift arm 34 is rocked (clockwise in FIGS. 1 and 4), the pin 36 will force the shaft 38 to the right to place a plurality of square root cams 50-1 to 50-12, inclusive (read-right to left in FIG. 1), carried thereby in operative alignment with the plurality of gear-engaging arms 70.

(1) *Cam shaft and drive (FIGS. 1, 3, 5 and 7).*—Square root cam shaft 38 carries a plurality of square root cams 50-1 to 50-12, one in each order of the square root selection mechanism (see FIGS. 1, 2 and 7). The cams 50-3 to 50-12 are identical in shape, and each is provided with a single tooth 52. These cams are so arranged on the shaft 38 that each tooth is spaced at an angle of 36° from the next tooth. Thus, the cam teeth 52 are arranged spirally around the shaft, separated from each other by an angle of 36°, so that in the highest ten orders, only one square root cam 50-3 to 50-12 will engage a pressure face of the associated gear-engaging arm 70 at any time. After the cam shaft 38 has been shifted to the right, it is rotated, or fed, to rock the respective ordinal cams 50-3 to 50-12 into operative position, in sequence as the carriage is shifted toward the left during square root extraction. That is, the cam shaft 38 is rotated an additional increment of 36° as the carriage shifts from one ordinal position to another, so that the respective gear-engaging arms (starting with the highest, or left-hand, order and progressing to the lowest, or right-hand order, in successive ordinal steps) become operative in sequence. By this means the control mechanism is enabled to select the orders in which the selection mechanism is to be adjusted.

The cam shaft 38 is driven by a stub shaft 53 (see FIGS. 1 and 5) journaled in a bracket 54 suitably supported on an auxiliary crossframe member 47 of the machine. The stub shaft 53 is connected to the cam shaft 38 by a suitable separable coupling and slip clutch device 55 which will permit the shaft 38 to be shifted to the right, and in the event of jamming of the mechanism, to permit relative rotation between the two plates of the coupling 55.

The stub shaft 53 is driven directly from the shifting of the carriage, whereby the stub and cam shafts always have an angular position determined by the lateral position of the carriage. The mechanism for securing this rotation of the stub shaft and cam shaft is shown particularly in FIGS. 1 and 5. The front carriage frame, or

rail, 56 is provided with a plurality of rack teeth 57 on the left-hand portion thereof. The rack teeth 57 are constantly in mesh with a pinion 58 which is rigidly fastened to a longitudinal shaft 59. This shaft 59 is supported in two arms of the bracket member 54 (see FIG. 5. A worm gear 60 is also rigidly journaled on the pinion shaft 59, and this worm 60 drives a gear 61 mounted on the stub shaft 53. Thus, the stub shaft 53, and through it, the cam shaft 38, are rotated with each ordinal shift of the carriage. As mentioned in my earlier patent, the gear train is so designed and constructed as to rotate the cam shaft 38 through an angle of 36° for each ordinal shift of the carriage.

It will be recalled that in my previous patent, No. 2,736,494, the carriage was free to shift through nine ordinal steps of movement. However, in the preferred form of my present invention, the shifting of the carriage is extended to eleven ordinal steps of movement (i.e., to twelve ordinal positions), whereby the extraction of square root is extended two orders. Thus, when the cam shaft 38 is rotated 36° for each ordinal step of movement of the carriage, the cam shaft, and the cams mounted thereon, will have a differential angular position for each ordinal position of the carriage. It might appear that this 36° rotation of the cams would cause an interference between the two highest order cams and the two lowest order cams. This would be true, except for the novel mechanism of the present invention, as will be described in detail hereinafter.

(2) *Gear-engaging arms (FIGS. 2 and 7).*—In each order of the square root programming mechanism, gear-engaging arms 70 are ordinally positioned against a plurality of ordinally arranged separator plates, as fully shown and described in the above-noted patent. In all orders of the square root mechanism, the gear-engaging arms 70 are identical in shape and size, are rockably journaled on the long shaft 46 previously mentioned (except the highest order arm as will be mentioned later), and are rocked by the single tooth 52 on the associated cam 50-1 to 50-11. The square root cams 50-1 and 50-2, associated with the first and second orders of the machine, are slidably but nonrotatably mounted on a square portion of the cam shaft 38 for preventing operation of cams 50-2 or 50-1 at the same time that cams 50-12 or 50-11 are operated, as will be described hereinafter. In the twelfth, or highest, order the gear-engaging arm 70 is pinned, or otherwise rigidly affixed, to the shaft 46, so that it will be rocked with the rocking of the shaft from operation of arm 42 (FIG. 6) described above. When so rocked, the pressure face 71 will be rocked away from the tooth 52 on the coordinate cam 50-12, and shaft 38 can shift to the right. Thereupon, tooth 52 of the cam 50-12 holds the highest order gear-engaging arm in its rocked position in spite of the fact that arm 42 was disabled to release pin 44 and shaft 46 by the shifting of cam shaft 38. In the other eleven orders, these gear-engaging arms are rocked only by the single tooth 52 on the square root cams 50-11 to 50-1. However, the tooth 52 of the twelfth order cam 50-12 will lie against the side of its associated gear-engaging arm 70, preventing the cam shaft 38 from being translated to the right into operative position, when the carriage is in the extreme right-hand position, unless shaft 46 is rocked. Each gear-engaging arm 70 is provided at its upper edge with a tooth-shaped pressure face 71 (FIG. 7) adapted to be engaged by the tooth 52 of the associated square root cam 50-12 to 50-1. The gear-engaging arm is also provided with a depending tail 73 which engages a stud 74 on the "1" to "5" selection bar 75 in the adjacent lower order of the selection mechanism. The degree of rocking of the gear-engaging arm 70 is so computed that the rocking of the arms, by the associated square root cam, moves the "1" to "5" bar 75 of the next lower order to the "5" position. Normally, the gear-engaging arm 70 is urged to an inoperative position (counter-

clockwise in FIG. 7) by a torsion spring 80. It is thus obvious that as the cam shaft 38 is rotated (counter-clockwise in FIG. 7) it successively brings its teeth 52 into rocking engagement with the respective gear-engaging arms 70. Rocking of a gear-engaging arm is operative to insert a value of "5" into the "1" to "5" selection bar 75 of the next lower order, and to move the coordinate feed gears 78 into mesh with the associated drive gear 79, as will be mentioned in the next subsection.

(3) *Feed gears and drive (FIG. 7).*—It is also necessary to drive the selection mechanism in a desired progression of single values beginning with the twelfth order of the selection mechanism and shifting order-by-order toward the right. For this purpose, I prefer to utilize, as I did in my former patent, No. 2,736,494, a plurality of feed gears 78, one for each order of the selection mechanism. These feed gears are slidably but nonrotatably mounted on a transversely extending square shaft 90 and are operable to rotate a plurality of ordinally arranged selection drive gears 79. Each gear-engaging arm 70 is also provided with an ear 72 adapted to engage a conically shaped hub 77 of the feed gear 78 and translates the feed gear to the left into mesh with the drive gear 79, upon rocking of the arm 70. A compression spring 91 is associated with each gear, and normally urges the gear 78 to the right to its inoperative position. Thus, the rocking of an arm 70 translates the respective feed gear 78 to the left against the bias of its spring 91, and in doing so, brings the gear 78 into mesh with the respective drive gear 79. Thereafter, the rotation of the shaft 90, which rotates all gears 78, drives the proper ordinal drive gear 79.

The drive gear 79 is used to drive the selection mechanism of its order a single step beginning with "1" in the second cycle of operation in order to provide the progression required in the "5's" method of square root extraction. Therefore, the feed gears 78 and the shaft 90 are given a single step of movement for each cycle of operation, beginning with the second cycle in each ordinal position of the carriage. In other words, no rotation of the shaft 90 is required for add-back, carriage shifting, and the first subtraction of "5." The mechanism for thus driving the square shaft 90 in single increments of motion is shown fully in my above-mentioned patent, and for the sake of brevity, will not be mentioned here, except to point out that the three-armed lever 1025 in FIG. 40 of Patent No. 2,736,494 is effective to cause rotation of the square shaft 90. Thus, through the gear 79, first, the "1" to "5" selection bar 75 and thereafter the "6" to "9" selection bar 76 will be fed one increment of movement for each increment of rotation of the shaft 90.

(d) Termination and Release

The square root operation is terminated, either by operation of a division stop key or the attempted over-shifting of the carriage beyond its extreme left-hand position. Upon termination of the square root operation, the square root cam shaft will be returned to the left, or its inoperative position. When the division operation terminates, the link 27 is pulled downwardly (by mechanism shown in FIG. 40 of Patent No. 2,736,494) and rocks the pusher arm 22 downwardly, releasing the lever 25. The cam shaft 38 (FIG. 1), under the force of its spring 39 (FIG. 2), is thereupon moved to the left to render the cams 50-1 to 50-12 ineffective. The downward movement of the link 27 also disengages the feed mechanism, i.e., the feed gears 78 shown in FIG. 7, from further operation. Therefore, regardless of whether the extraction operation is terminated by operation of the conventional stop key, or by completing the extraction in the lowest, or extreme right-hand, order of the machine, the square root shaft is unlatched by link 27 and returned to the left to its normal inoperative position.

III. EXTENDED SQUARE ROOT MECHANISM

(A) Additional Cams (FIGS. 1 and 8)

It was mentioned in the earlier part of this disclosure that a primary object of the invention is to extend the number of orders from which the root of a radicand can be extracted in the commercial square root calculating machine, as disclosed in my patent, No. 2,736,494, without redesigning the machine or changing the timing thereof.

In order to accomplish the objects of this invention, I prefer to lengthen the square root shaft 38 and mount a pair of additional square root cams thereon for controlling the extraction of square root through two more orders for the machine without changing the timing of the machine. In the preferred form of the present invention the right-hand end portion of the square root cam shaft 38 is substantially square in cross-section (see FIGS. 1, 7 and 8). It is on this square portion of the shaft that I slidably and nonrotatably mount two additional square root cams 50-2 and 50-1 (FIG. 1) for controlling the extraction of square root from the lowest, or first and second, orders of the machine. As best shown in FIG. 8, I prefer to mount the two cams 50-2 and 50-1 on a common hub, or spool, 51, so that they can be operated in unison. All of the square root cams 50-12 to 50-1 are successively staggered at 36° on the cam shaft and, in accordance with the novel construction of the present invention, both cams 50-12 and 50-2 lie in the same angular position on the shaft, and cams 50-11 and 50-1 also lie in the same angular relationship to the shaft. Obviously, in my prior patent, the cams in the twelfth and second orders would be operative simultaneously, and likewise the cams in the eleventh and first orders. The present mechanism is designed to avoid this difficulty, and thus enables the cams to operate sequentially, and without any duplicate operation, even though two pairs of cams occupy the same angular position.

In the present machine I avoid the above-noted difficulty by shifting the two additional square root cams 50-2 and 50-1 (rightward as seen in FIG. 1) on the square root shaft 38 into operative position after the higher two orders of square root is extracted, by mechanism explained in the next section. By delaying the shifting of the two additional cams 50-2 and 50-1 into alignment with their respective gear-engaging arms 70, the tooth 52 of the highest two cams 50-12 and 50-11 rocks the gear-engaging arm associated with these two orders before the additional cams become operative. Furthermore, before the two additional cams 50-2 and 50-1 become operative to rock their respective gear-engaging arms 70, the highest two square root cams 50-12 and 50-11, and incidentally cams 50-10 to 50-3, are shifted (leftward as seen in FIG. 1) out of alignment with the gear-engaging arms associated with these cams, by the mechanism explained in Section C hereinafter. By these means I am enabled to avoid operation of each angularly identical pair of square root cams simultaneously. Therefore, I provide a machine for extracting twelve orders of square root with the same machine timing as provided in the conventional ten-order square root machine.

The two additional square root cams 50-2 and 50-1 are shifted rightwardly on the square portion of shaft 38 after three orders of square root have been extracted. In this way the teeth 52 on the highest two cams 50-12 and 50-11 have rocked their respective gear-engaging arms 70 before the lowest two-order cams 50-2 and 50-1 are shifted into alignment with their respective gear-engaging arms. Furthermore, before the two additional cams 50-2 and 50-1 become effective to rock their respective gear-engaging arms 70, the main portion of the square root cams 50-12 to 50-3 is shifted out of alignment with the arms 70. In this way, I have provided

a machine for extracting twelve orders of square root with the same machine timing as provided in the conventional ten-order square root machine.

(B) Control Slide for Additional Cams

The two additional square root cams 50-2 and 50-1 (which are preferably formed on the common hub, or sleeve, 51) are shifted rightwardly on the square portion of the cam shaft 38 by means of a control slide 101 extending across the rearward edge of the keyboard. The slide 101 is slidably mounted on a pair of brackets 103 by any suitable means, such as screws 104, threaded into the brackets and extending through slots 105 in the slide (see FIGS. 2 and 7), the brackets being affixed to the square root control box indicated at 99 and fully shown and described in the above-noted patent. The control slide 101 is urged to the left by a spring 106 connected to one of the screws 104 and a pin 107 affixed to the slide 101. Subsequent to rightward movement of the control slide 101 and the two cams 50-2 and 50-1 against the tension of the spring 106, the slide and cams will be latched in operative position, by latching means described hereinafter, until the square root operation is terminated.

As best seen in FIGS. 1 and 8, the two additional square root cams 50-2 and 50-1 are constructed with the common hub 51 which is provided with a suitable square aperture for mating with the square portion of the shaft 38 and an annular groove 100 for controlling coaxial movement of the cams. Embraced within the groove 100 is a pin 102 affixed to, and extending downwardly from, an arm protruding rearwardly from the right-hand end of the control slide 101. The pin 102 rides within the groove 100 at all times and thereby effects shifting of the extra square root cams 50-2 and 50-1 whenever the slide 101 is caused to shift from its inactive to its active control position, by means to be described next. Obviously this shifting could be done at any time after the completion of operation in the eleventh order and prior to initiation of operation in the second. It is more convenient, however, to shift these cams as the control mechanism has completed three ordinal series of operations, i.e., at the time cam shaft 38 rocks cam 50-9 to its effective position. As was mentioned under Section II, Subsection (b) (1) above, lever 25 and arm 34 are effective, upon initiation of the division operation, to move the cam shaft and cams 50-12 to 50-3 thereon into operative position for causing the square root extraction operation. However, in the preferred form of the present machine the extra cams 50-2 and 50-1 are not moved rightwardly into operative position until three ordinal series of operations have been completed, i.e., until the cam shaft 38 has rotated at least 72°. In order to shift the control slide to the right 55 I provide the ninth order square root cam 50-9 (i.e., the fourth cam counting from left to right) with an ear 110 extending rightwardly from the web of the cam 50-9. Actuating ear 110 is provided with an inclined cam face which, during the third rotation of the cam 50-9 shaft 38, engages a pin 111 affixed to, and extending downwardly from, a rearwardly projecting finger of the control slide 101, thereby camming the slide rightwardly. It will be recalled that the shaft 38 is shifted to the right, as viewed in FIG. 1, to place the square root cams 50-12 to 50-3 in operative position. Rightward movement of the shaft 38 brings the actuating ear 110 into the plane of pin 111. About midway through the third increment of rotation of the square root cam shaft 38, the cam face of ear 110 engages pin 111 and forces the control slide 101 toward the right. As was mentioned earlier, rightward movement of the control slide 101 shifts the two additional cams 50-2 and 50-1 rightwardly on the square portion of shaft 38. Thus, the additional square root cams 50-2 and 50-1 are moved into operative position after the first three cams, 50-12

50-11 and 50-10, have caused the extraction of the square root from the highest three orders of the accumulator.

It can be mentioned again that the actuating ear 110 could have been constructed on the web of any of the square root cams, except cams 50-12 or 50-11, because the rotation of these two cams occurs too early in the square root operation for placing the additional cam in operative position. The use of cam 50-3 would also be undesirable because its operation occurs too late in the machine operation to effectively place the additional cams in operative position. I chose to place the actuating ear 110 on the ninth order cam 50-9 where it would cause the rightward movement of the control slide 101 after the square root shaft 38 is rotated at least 72° and after the highest three cams have tripped the gear-engaging arms 70, as this location of the actuating cam works best with a resetting device, which will be described hereinafter in Section (D). It will be recalled that the shaft 38 rotates one increment each time the carriage is shifted from one ordinal position to another but, unless the shaft 38 is moved to the right, the actuating ear 110 is not in the plane of the pin 111 and will bypass the pin. Hence, the control slide 101 is not moved in machine operations involving operations other than square root. However, when the slide is adjusted during a square root operation, it will be latched in its adjusted position by mechanism now to be described.

In order that the spring 106 will not be effective to return the two lowest order cams 50-2 and 50-1 to their normal inoperative positions, I provide a means for latching the slide 101 in its operative position until the square root operation is terminated. Affixed to the ear 28 (FIG. 5) of the previously mentioned link 27 is a pin 115, best seen in FIGS. 3 and 4. Pin 115 normally lies slightly below a leaf spring 116 fastened by any suitable means, such as screws 117, to a leftwardly extending arm 118 of the control slide 101 (see FIGS. 1 and 4). It will be recalled that link 27 is urged upwardly upon initiation of the square root operation. Upward movement of the link 27 will cause the pin 115 to bend the leaf spring 116 upwardly, and the spring will remain deformed until the control slide 101 is shifted to the right by the actuating cam 110, previously mentioned. Upon rightward movement of the slide 101, the leaf spring 116 is snapped back to its normal condition, whereupon the leftmost edge of the spring 116 will abut the pin 115 and latch the control slide 101 in its rightward shifted position, against the urgency of its spring 106. It will be recalled that when the square root operation is terminated, as explained in Section II, Subsection (d) above, the link 27 is pulled downwardly. Thus, the pin 115 is removed from engagement with the leaf spring 116 and the spring 106 will return the slide 101 and the two additional cams 50-2 and 50-1 to their inoperative position.

(C) *Cam Shaft Release Mechanism (FIGS. 1 and 5)*

In order to prevent simultaneous operation of the twelfth and second order cams, and also the eleventh and first, it is not only necessary to shift cams 50-1 and 50-2 to their operative position after operation is completed in the eleventh order, it is also necessary to disable the twelfth and eleventh before operation can start in the second order. Again, means could be provided to disable cams 50-11 and 50-12 at any time after operation is completed in the eleventh order. However, it is more simple and satisfactory to disable all the cams on shaft 38, i.e., cams 50-3 to 50-12, inclusive, with one operation. Thus, after ten orders of square root have been extracted and the carriage starts its eleventh shift operation, i.e., from the third to the second coordinal position, the main portion of the square root cams (50-12 to 50-3) is released to return to their normal inactive position while the additional square root cams 50-2 and 50-1 remain in their operative position throughout the remaining two orders of square root operation.

When the carriage 56 shifts from its third to its second coordinal position (i.e., after ten ordinal series of square root operations), a roller 121 (FIG. 1) fastened to the front carriage rail 56 of the accumulator carriage contacts a cam surface 122 on the rearward edge of a cam shaft releasing slide 123. The slide 123 is slidably mounted on a bracket 124 extending rightwardly from the side frame of the machine, the slide 123 being mounted by any suitable means, such as a pair of pins 125 extending upwardly from the bracket 124 into suitable slots 126 provided in the slide 123. In FIG. 1 the roller 121 is shown in the position that it will occupy during the tenth order of square root extraction. During the next, or eleventh, leftward shift of the carriage, the roller 121 forces the cam shaft releasing slide 123 forwardly against the tenison of a spring 127 connected between one of the pins 125 and a stud 128 fixed to the slide 123. Forward movement of the slide 123 is effective to cause the pusher arm 22 (FIG. 5) to release the square root cam shaft 38 (FIG. 1) for return to the left, or normal inactive position, under force of the coil spring 39 (FIG. 2).

Referring to FIGS. 3 and 5, the releasing slide 123 has a downwardly extending ear 129, which ear is provided with an inclined cam surface 130 for engaging the pin 26. As best seen in FIG. 5, the forward movement of the slide 123 (to the left in this figure) causes the cam surface 130 to engage the pin 26 and rock the pusher arm 22 downwardly (clockwise). The rocking of the pusher arm 22 releases the cam shaft shift lever 25, whereupon the cam shaft 38, under the force of its spring 39, is moved to the left and renders the first series of cams 50-12 to 50-3 ineffective. After the pusher arm 22 is rocked, it will lie below the lever 25 and so it is ineffective to cause a second rightward shifting of the square root cam shaft 38 until another square root operation is initiated and the shaft 20 is first rocked clockwise and then counter-clockwise, as was mentioned in Section II, Subsection (b) above. Thus, the first series of square root cams 50-12 to 50-3 are shifted to their inoperative position after ten orders of square root have been extracted, while the additional, or second, series of cams 50-2 and 50-1 remain in their operative position. These cams will remain in their operative position until the link 27 is pulled downwardly upon termination of the square root operation. It should be mentioned here, that in the above-described preferred form of my invention, the square root cam shaft 38 is rotated a total of 396°. Even though the cams are set at an angular distance of 36° apart (the spacing of the prior machine), there will be no simultaneous operation of, or interference between, the cams 50-12 and 50-11 associated with the highest two orders of the machine and the cams 50-2 and 50-1 associated with the lowest two orders of the machine to cause an extraction from two orders at the same time. After ten orders of square root have been extracted, the highest ten orders of square root cams are returned to their normal inactive position, while the other two square root cams remain in their operative position until the square root operation is terminated. Upon termination of the operation, the square root cams 50-2 and 50-1 of the lowest two orders are returned to their inoperative position (by release of slide 101) where they will remain until they are again moved to the left by the actuating cam 110.

(D) *Automatic Resetting of Cam Shaft (FIGS. 1 and 9)*

If for any reason, the square root cam shaft 38 is blocked against rotation, the coupling slip clutch 55 will slip until the obstruction is removed. When this happens, the cam shaft will be out of time relative to the ordinal position of the carriage, because in square root extraction, the rotation of the cam shaft is dependent upon the order-by-order shifting of the carriage, as previously described. In the present machine I provide means for automatically

retiming the cam shaft 38 relative to the carriage whenever the carriage is shifted to either of its extreme end positions. As previously mentioned, at the beginning of the square root operation, the carriage is shifted first to its extreme left-hand position, and the accumulator is cleared; and then the carriage is shifted to its extreme right-hand position before the actual extraction operation begins. Thus, I can provide a means, utilizing the extreme movement of the carriage, for retiming, or resetting, the square root cam shaft before the shaft is shifted into its operative position for controlling the extraction of square root.

Referring now to FIGS. 1 and 9, there is shown a bracket 135 fastened to the auxiliary crossframe 47 of the machine by a screw 136. The bracket 135 extends forwardly from the crossframe and partially surrounds the square root cam shaft 38 adjacent the right side of the seventh order square root cam 50-7. Rockably and nonslidably mounted on the shaft 38, next to the bracket 135, is a substantially U-shaped aligner 138 (FIG. 1). The aligner 138 includes left and right arms 139 and 140, respectively, depending from a narrow bar 141. The left arm of the aligner 138 carries a short pin 142 (FIG. 9) extending to the left into an arcuate notch 137 provided in bracket 135. For purposes which will become apparent hereinafter, the pin 142 and notch 137 prevent the aligner 138 from rotating through an angle greater than 72°. Depending on the angular position of the cam shaft 38, the tooth 52 of the sixth order square root cam 50-6 will lie to either side of the bar, or bridge, 141 of the aligner 138, for causing limited rotation of the aligner.

FIG. 9 shows the aligner 138 and the sixth order cam 50-6 in the position they assume at the beginning of the extraction phase of the square root operation. After ten orders of square root extraction, and before the shift to the next ordinal position, the tooth 52 of the cam 50-6 has rotated 324° to a point where it is against the rearward side (left in FIG. 9) of the aligner 138 which has not yet been rotated. During the following two orders of square root extraction, the tooth 52 of cam 50-6 will force the aligner 138 to rotate through an angle of 72°, moving the pin 142 from the position shown in FIG. 9 into contact with the forward edge of the arcuate notch 137, thereby preventing any further rotation of the square root cam shaft 38 (clockwise in FIG. 9). Conversely, upon rotation of the cam shaft 38 in the other direction (counter-clockwise in FIG. 9), the sixth order cam 50-6 will rotate until the tooth 52 hits the bridge 141 of the rocked aligner 138. Further rotation of the cam shaft will return the aligner to the position shown in FIG. 9 whereupon the pin 142 once again abuts the rearward edge of the notch 137 and prevents further rotation of the shaft.

Suppose now that during leftward shift of the carriage, rotation of the square root cam shaft 38 is blocked after rotating 108°, further leftward shifting of the carriage will cause the slip clutch 55 (FIG. 1) to slip and prevent damage to the machine. If, after the obstruction is removed, the carriage is shifted toward its extreme right-hand position, the cam shaft is then rotated in the opposite direction the previously rotated 108°, after which the aligner 138 stops further rotation of the shaft. As the carriage continues to shift toward the right, the slip clutch 55 will yield until the carriage is in its extreme right-hand position, thereby automatically retiming, or resetting, the cam shaft to the carriage position for effecting square root operations. After the obstruction which blocked rotation of the cam shaft 38 is removed and the carriage is shifted to either of its extreme positions, the pin 142 will abut either edge of the arcuate notch 137 to cause the slip clutch 55 to slip until the carriage reaches its extreme position which, as can be seen, automatically retimes the cam shaft relative to the carriage. Therefore, I provide a novel resetting device for the square root

cam shaft which will automatically retime the shaft if, for any reason, the shaft is blocked during a machine operation.

(E) *Operation*

5 It is believed that the operation of my invention for extracting twelve orders of square root will be readily understood from the above description. However, it can be mentioned briefly that after the radicand is set into the accumulator and the carriage is in its extreme 10 right-hand position, the pusher arm 22 (FIG. 5) will effect a right shift of the square root cam shaft, as explained in Section (b), Subsection (1) above, and the cam shaft will be latched for ten orders of square root extraction. After the root is extracted from the highest 15 three orders of the machine, the rotation of the square root cam shaft causes the actuating gear 110 (FIG. 1) on square root cam 50-9 to drive against the pin 111 (see Section III, (B)) and shift the slide 101 to the right for bringing the additional square root cams 50-2 and 20 50-1 (Section III, (A)) into operative alignment with their associated gear-engaging arms 70 (FIG. 7), for the remaining orders of square root extraction. It will be recalled that upon initiation of the square root operation, the upward movement of the link 27 causes the pin 115 25 thereon (FIGS. 1 and 5) to bend the leaf spring 116, on the left-hand portion of slide 101, whereby pin 115 blocks return of the slide after it is shifted to the right. As the register carriage makes its tenth leftward shift, the roller 121 (FIG. 1) drives the cam shaft release slide 123 30 (Section III, (C)) forward, which slide drives the pusher arm 22 downwardly for releasing the square root cam shaft 38 and the main portion of the square root cams 50-12 to 50-3, which cams then return to their inactive position. However, the additional cams 50-2 and 50-1 35 remain in the active position until the square root operation is terminated by an attempted overshift of the carriage. The termination of a square root operation (Section 40 (d)) forces the link 27 and pin 115 to move downwardly and release the slide, as well as the additional cams 50-2 and 50-1. Thus, upon completion of the square root operation, all of the square root cams 50-12 to 50-1 will have returned to their home position.

From the foregoing description of a preferred form of my invention, it is seen that I have provided a mechanism 45 for solving the exasperating problem of building a twelve-order machine for extracting square root without completely redesigning the commercial machine made in accordance with the teaching of United States Patent No. 2,736,494. With my invention, the square root cams are 50 still spirally staggered at 36° on the cam shaft, but now the cam shaft is rotated 396° to cause extraction of square root from twelve orders of the machine. This is so because the lowest order cams are not shifted into operative position until the cam shaft has caused operation in 55 the two highest orders at least, and preferably has rotated 72°. Furthermore, the cams associated with the higher orders of the machine are out of operative position before the cams associated with the lowest orders of the machine become effective to cause the extraction of the 60 root from these orders.

Although the present invention has been described with respect to a single embodiment, it will be appreciated by those skilled in the art that numerous modifications and variations thereof are possible within the spirit and scope 65 of the invention, and thus, the invention is not to be limited except by the terms of the following claims.

I claim:

1. In a calculating machine for the extraction of square root having:
  - an ordinarily arranged selection mechanism, adjusting means operable to progressively adjust each order of the selection mechanism in increments corresponding to a "1," setting means for inserting a value of "5" in each order of said selection mechanism,

15

means for operating said setting means in one order and operating the said adjusting means in the next higher order,

a cam shaft,

means for rotating said cam shaft, and

ordinally arranged cams mounted spirally on said cam shaft for operating said operating means in an ordinarily diminishing sequence,

a mechanism for extending the number of orders in which square root can be extracted without changing the timing of the machine comprising:

additional cams slidably mounted spirally on said cam shaft for effecting the extraction of the root, and control means for slidably moving said additional cams relative to said cam shaft in timed relationship with the rotation of the shaft.

2. In a calculating machine for the extraction of square root having:

an ordinarily arranged selection mechanism,

means for inserting a value of "5" in a preselected order of said selection mechanism,

setting means operable to progressively adjust said selection mechanism of the next higher order to said preselected order in increments corresponding to a value of "1,"

ordinarily operative adjusting means operable to adjust said setting means for operation in successive ordinal positions,

a cam shaft axially adjustable from an inactive to an active position,

mechanism for axially adjusting said cam shaft in timed relationship with the operation of said machine, and

ordinally arranged cams mounted spirally on said cam shaft for operating said first mentioned adjusting means in an ordinarily diminishing sequence,

a mechanism for extending the number of orders from which the square root of the radicand can be extracted without changing the timing of the machine comprising:

a pair of cams each slidably mounted spirally on said cam shaft,

a means for shifting said pair of cams along said cam shaft from an inactive to an active position in timed relationship with the axial adjustment of said cam shaft, and

mechanism for effecting the return of said cam shaft to its inactive position prior to the termination of the square root extraction operation without effecting the position of said pair of cams whereby said pair of cams continue to operate said adjusting means in the aforementioned ordinarily diminishing sequence.

3. The aperture of claim 2 comprising also

a means for latching said pair of cams in their actively adjusted position subsequent to the return of said cam shaft to its inactive position, and

means for releasing said latching means upon termination of the square root operation thereby returning the pair of cams to their inactive position.

4. In a square root calculator having:

an ordinarily arranged selection mechanism,

means for inserting a value of "5" in a preselected order of the selection mechanism,

setting means operable to progressively adjust the selection mechanism of the next higher order in increments corresponding to a value of "1,"

ordinarily operative adjusting means operable to adjust the inserting means and the setting means for operation in successive orders,

a cam shaft axially adjustable from its inactive to its active position for controlling operation of said adjusting means,

means operable for rotating said cam shaft through a predetermined angular movement, and

a first series of ordinarily arranged cams mounted spirally on said cam shaft for operating the adjusting

means subsequent to positioning of said cams relative to the adjusting means in an ordinarily diminishing sequence,

a mechanism for extending the number of orders from which the square root of a number can be extracted without changing the timing of the machine comprising:

a second series of ordinarily arranged cams slidably mounted spirally on said cam shaft at the end thereof for operating said adjusting means subsequent to positioning of these second series of cams relative to the adjusting means.

means for sliding said second series of cams along said cam shaft from an inactive to an active position in timed relationship with the rotational adjustment of said cam shaft,

said last mentioned means including a means effective after at least 72° rotation of said cam shaft for operating said sliding means, and

mechanism for effecting the return of said cam shaft to its inactive position after ten orders of square root have been extracted without altering the position of said second series of cams.

5. In a machine for extracting the root of a number having:

an ordinarily arranged selection mechanism,

setting means operable to progressively adjust each order of the selection mechanism in increments corresponding to "1,"

means for inserting a value of "5" in each order of said selection mechanism,

means for adjusting said inserting means in one order and operating said setting means in the next higher order,

a cam shaft,

means for rotating said cam shaft through a predetermined angular movement, and

ordinally arranged cams mounted spirally on the said cam shaft for operating said adjusting means in an ordinarily diminishing sequence,

a mechanism for extending the number of orders from which a root of a number can be extracted without changing the timing of the machine comprising:

additional cams slidably mounted spirally on said cam shaft for effecting the extraction of the root in additional orders,

control means for slidably moving said additional cams relative to said cam shaft in timed relationship with the rotation of the shaft, and

a cam shaft resetting means for automatically retiming said cam shaft upon initiation of a machine operation.

6. A cyclically operable square root calculating machine comprising the combination of:

an ordinarily arranged selection means,

a feed shaft rotatable through a predetermined angular movement with each cycle of machine operation,

a plurality of ordinarily arranged connecting means positionable to operatively connect said feed shaft to an ordinarily associated selection means,

means for sequentially positioning said connecting means in connecting position, said last-mentioned means including a cam shaft,

mechanism operable for rotating said cam shaft through an intermittent angular movement,

a first series of ordinarily arranged cams mounted spirally on said cam shaft,

a second series of ordinarily arranged cams slidably and nonrotatably mounted spirally on said cam shaft,

and cam followers for said first series and said second series of cams operative to position said ordinarily associated connecting means in connecting position,

means for sliding said second series of cams axially of

75

said cam shaft in timed relationship to the angular rotation thereof, and
 means operated by said cam follower for inserting a value of "5" in the next lower order selection means.
 7. The apparatus of claim 6 comprising also a means for axially moving said cam shaft from an active to an inactive position prior to operation of said second series of cams, and a latch means for said second series of cams to

retain said cams in their active position after return of said cam shaft to its inactive position.
